UNITED STATES PATENT OFFICE.

WARD S. IRELAND, OF ST. LOUIS, MISSOURI, ASSIGNOR TO NATIONAL SHORTHAND MACHINE COMPANY, OF ST. LOUIS, MISSOURI, A CORPORATION OF DELAWARE.

SHORTHAND-MACHINE.

1,524,550.

Specification of Letters Patent. Patented Feb. 21, 1919.

Application filed February 21, 1917. Serial No. 150,054.

To all whom it may concern:

Be it known that I, WARD S. IRELAND, a citizen of the United States of America, a resident of the city of St. Louis, State of Missouri, have invented certain new and useful Improvements in Shorthand-Machines, of which the following is a full, clear, and exact description, reference being had to the accompanying drawings, forming a part of this specification.

My invention relates to improvements in shorthand machines, and more particularly to a shorthand keyboard and printing elements associated therewith. By the term "shorthand machine" I mean a machine having a number of keys adapted to be actuated simultaneously so that a collection of letters constituting a word or part of a word may be printed or written quickly by a single stroke of one or both of the operator's hands. The printed characters may spell the word properly, phonetic spelling may be resorted to, or a code may be used in lieu of such spelling.

One of the objects of the invention is to produce a simple shorthand printing device having its parts so constructed and arranged that a great variety of shorthand expedites may be printed through the medium of a simple keyboard. A further object of the invention is to simplify the art of shorthand writing by enabling the operator to write, or print, in very clear type, many different characters which, heretofore, have been only vaguely represented by arbitrary combinations of characters.

Another object of the invention is to produce a new shorthand machine keyboard having a highly desirable combination of conveniently arranged keys under the immediate control of the thumbs and fingers of the operator.

With the foregoing and other objects in view the invention comprises the novel construction, combination and arrangement of parts hereinafter more specifically described and illustrated in the accompanying drawings wherein is shown the preferred embodiment of the invention, however, it is to be understood that the invention comprehends changes, variations and modifications which come within the scope of the claims hereunto appended.

The shorthand machine I have shown to illustrate the preferred form of the invention is provided with means for printing

upon and feeding a strip of paper. The keyboard includes keys which may be operated independently of each other, or several keys may be operated simultaneously to print a line of characters. During each key operation, the paper advances one step irrespective of the number of keys used in printing the character or characters.

It is an advantage to minimize the number of keys, for all of the keys used in each printing operation must be depressed simultaneously and they should be within the reach of and easily controlled by the fingers of the operator. However, it is a decided disadvantage to reduce the number of type characters to such an extent that many complex combinations of characters are required to represent missing characters. Heretofore, numerals have been represented by combinations of alphabetical characters, and also by combining alphabetical characters with another character to indicate that the printed matter is a code representing one or more numbers. In following the last mentioned method, the operator must depress one key to print the number-indicating character, and at the same time manipulate the alphabetical keys to print the alphabetical characters which are to be read as numerals. Moreover, in transcribing the notes the operator must watch carefully for the distinguishing character indicating that the alphabetical characters represent numerals.

To economize in the manufacture of the machines, and to avoid unnecessary weight, it is desirable to reduce the number of key levers and other parts to a minimum. It is also an advantage to construct the printing elements in such a manner that a great variety of characters may be selected and printed on a relatively narrow strip of paper. This reduces the weight of the paper roll, and, furthermore, it is comparatively easy to read the relatively short lines of characters.

To obtain all of the foregoing advantages, more particularly the highly important advantage of enabling the operator to write words very rapidly, the printing type consists of what I term primary and secondary characters, and the finger keys have been so constructed and arranged that all of the selected keys may be actuated quite easily and very quickly. Before describing a specific structure, I will endeavor to more clearly explain the reason for using the

terms "primary" and "secondary" characters, and point out the beneficial results derived from the new combination and arrangement of keys and type characters.

- 5 The group or groups of characters used most frequently have been termed "primary" characters, and the characters not used so often are the "secondary" characters. For example, a carefully selected 10 group or groups of alphabetical characters may be considered as the primary characters, and numerals may be the secondary characters. Or, if desired, the secondary characters may include a carefully selected 15 group of supplemental letters which provide for the printing of a very large number of words that could not be conveniently printed by the primary characters alone. In this connection it is important to observe that 20 the art of machine-shorthand involves a very comprehensive scientific study of words, and, as a result of considerable study, I have found that certain combinations of "primary" characters occur very frequently, 25 while the "secondary" characters do not appear so often. However, the secondary characters are quite important, and the printing of such characters should be easily controlled by the hands of the operator.
- 30 If the keyboard is so constructed that all of the primary and secondary characters may be printed simultaneously in a single line, the line would be very long, and the desired keys could not be readily selected 35 and depressed at a single stroke. Again, if the use of a large collection of printing keys is avoided by employing ordinary individual shift keys, one or more fingers must be used to shift the type, and, therefore, cannot be 40 used to operate the printing keys. To obtain maximum speed, which is the main object in shorthand writing, each of the operator's fingers should be free to actuate a character key, and it is apparent that this 45 cannot be done if one or more fingers are used for the sole purpose of actuating one or more individual shift keys. Consequently, the highly desirable maximum speed cannot be obtained if any of the fingers are required 50 to perform the sole function of actuating a shift key.
- I will now briefly describe a specific structure whereby I overcome all of these disadvantages.
- 55 The printing elements include primary and secondary type characters arranged in different lines, a collection of primary keys, and a secondary key, or shift key, for moving the secondary characters to the printing 60 line. The primary characters are printed by actuating the primary keys, and all of said primary characters may be printed simultaneously in a single line, by depressing all of the primary keys at the same time.
- 65 The secondary key, or shift key, is prefer-

ably associated with a series of the primary keys, and if all of the keys of this series are depressed with the secondary key, all of the secondary characters will be printed in a single line. Any one or more of the 70 last mentioned series of primary keys may be selected and depressed with the secondary key for the purpose of printing the selected secondary characters.

Stated more specifically, one of the principal features of the invention consists in combining the secondary key with a series of the primary keys, in such a manner that any of the secondary characters may be printed by a single stroke of a single finger. 75 The same is true of the primary characters. In other words, the machine is provided with both primary and secondary characters, and any of the characters may be selected and printed by only one finger.

Figure I is a diagrammatical view of the printing element.

Fig. II is a plan view of the machine, portions of the housing being broken away.

Fig. III is a longitudinal section of the 90 machine shown in Fig. II.

Fig. IV is a detail view showing primary and secondary keys, and the shiftable type carrier operable by the secondary keys.

Fig. V is a perspective view of the shift- 95 able type carrier.

Fig. VI is a transverse section taken approximately on the line VI—VI, Fig. III.

Fig. VII is a fragmentary view illustrating a modification.

Fig. VIII is a view similar to Fig. VII, 100 showing a further modification.

The keyboard I have shown to illustrate a preferred form of the invention comprises a group of primary initial consonant keys 105 D, G, K, S, B, T, P, H, L and R, a group of vowel keys O, A, I, E and U, and a group of primary final consonant keys L, R, N, M, B, T, G, L, Y and S. If all of these keys are depressed simultaneously, all of the primary consonants will be printed with the vowels in a single line as shown at the upper portion of Fig. I. A star may be printed by depressing the elongated key which lies between the initial and final consonant 115 keys. Any of these primary keys, or a combination of primary keys, may be selected and depressed simultaneously to print any selected primary character or characters.

10 designates a shift bar provided with 120 a series of individual secondary initial consonant keys J, V, Y, M and N, associated with the primary keys G, S, T, H and R, as will be hereinafter described. A shift bar 11 is provided with a row of secondary final 125 consonant keys R, L, T, C and H associated with the adjacent primary keys R, M, T, L and S. The secondary keys 1, 2, 3, 4 and 5, located at the rear of the primary initial consonant keys, are carried by a shift bar 130

12 and associated with the primary keys D, K, B, P and L to print the numerals 1 to 5. A shift bar 13 is provided with individual secondary keys associated with the rear row 5 of final consonant keys to print the numerals 6, 7, 8, 9 and 0. If all of the primary and secondary keys are depressed simultaneously, all of the secondary characters will be printed in a single line as shown at the upper portion of Fig. I. I will now point out briefly how this is accomplished and afterward describe the various details of construction.

The printing elements include a line of type for printing the primary characters (Figs. I and V) and a second line of type for printing the secondary characters. The primary keys normally print the primary characters, but when a secondary key is depressed it actuates a shifter, at the same time actuating one of the primary keys to print a secondary character. Each primary key may be operated by itself to print a primary character, and it may be operated simultaneously with a secondary key 25 to print a secondary, instead of a primary character. For example, the primary key G at the left side of Fig. I may be operated by itself to print the primary consonant G, or it may be actuated with the secondary key J and shift bar 10 to print the secondary consonant J. The shift bar 10 may be actuated simultaneously with the adjacent primary initial consonant keys 30 G, S, T, H and R to print all of the secondary consonants J, V, Y, M and N, or, any one of the last mentioned primary keys may be selected and depressed with the shift bar 10 to print the secondary initial consonants J, V, Y, M and N. In the keyboard I have 35 shown, each secondary key is adapted to actuate a companion primary key to print a secondary character. For instance, the secondary key J is adapted to actuate the primary key G, as will be hereinafter pointed out, to print the secondary character J. Any final consonant represented by the secondary keys R, L, T, C and H shift bar 11 may be printed by depressing the selected secondary key, thereby actuating a primary key and the shift bar 11 to print the secondary character. For example, the secondary final consonant H (Fig. I) may be printed by depressing the keys H and S at the right side 40 of Fig. I, at the same time depressing the shift bar 11, and the operator may accomplish all of this by merely actuating the secondary key H. In a similar manner, the shift bars 12 and 13 and their secondary keys 45 may be actuated with the adjacent primary keys to print selected numerals instead of printing the primary characters which appear on the primary keys.

For the purpose of this disclosure, I have shown the various primary and secondary 50 characters on the keys, but a skilled oper-

ator will actuate the keys without the aid of visible characters, and I, therefore, prefer to use a "blind keyboard". Furthermore, any desired primary or secondary characters may be used, and the characters may be arranged in any desired sequence.

The shift bars 10 and 12 are secured together, as will be later described, to shift a type carrier. The shift bars 11 and 13 are likewise secured together to actuate another 75 shiftable type carrier. The different shifters are operable independently of each other so that primary and secondary characters may be printed simultaneously. For example, in the word Man, "M" is a secondary initial 80 consonant, "A" is a vowel, and "N" is a primary final consonant. All of these letters may be readily printed simultaneously by depressing the secondary key M thereby actuating the shifter and the primary key 85 H to print the secondary consonant N, at the same time actuating the vowel key A and the primary final consonant key N. The word "Man" is thus printed very quickly by combining the primary and secondary 90 characters. This is a very simple illustration, but it will be apparent that an indefinite number of words may be printed by combining the primary characters of one group with the secondary characters of another group.

The secondary keys do not in any way interfere with the primary keys, the operator being free to select and print primary characters in the usual manner. When the 100 desired characters appear in the secondary division, they may be readily printed by depressing primary and secondary keys at the same time. In this connection, it will be important to observe that each secondary 105 key is adapted to transmit movement to its companion primary key, as will be more fully explained, so that both keys may be depressed simultaneously by a single stroke of a single finger. The value of this feature 110 may not be fully appreciated, unless it is clearly understood that speed is a most important factor in shorthand writing; the keys to be operated at a single stroke must all be under the convenient control of the 115 operator's fingers, and the operator should be able to easily select and print a maximum number of characters at a single stroke. Heretofore, characters which I term "secondary" have been missing from the keyboard 120 so that a complex code is required to represent them; or they have been printed by using one or more fingers to operate one or more ordinary shift keys, at the same time using one or more additional fingers to actuate selected printing keys. Consequently, the operator has heretofore been 125 unable to print all of the selected characters at the high rate of speed that could be obtained by using a single finger to clearly 130

print any desired "secondary" character. The machine I have shown is so constructed that any selected primary character, or any selected secondary character may be printed by a single stroke of a single finger.

The strip of paper 14, upon which the characters are printed, passes from a supply roll 15, under an idler rod 16 (Fig. III) thence upwardly over a feed roll 17, down-
10 wardly through an inclined guideway 18, and then rearwardly to a discharge opening at the rear of the machine. Rotatable ribbon spools 19 (Fig. III) located near the rear of the machine, are adapted to feed the 15 inking ribbon 20. Rods 21 guide the inking ribbon during its movement from one spool to another.

The type support preferably comprises a stationary horizontal rod 22, rigidly secured 20 at its ends to side frames 23. A middle type section 24 is rigidly secured to the stationary rod 22 by means of a pin 25 (Figs. V and VI). The bottom face of this stationary type section is provided with a star and the 25 vowel characters O, A, I, E and U. Shiftable type sections 26 and 27, pivotally supported by the stationary rod 22, are each provided with a row of primary type characters and a row of secondary type characters. The 30 primary initial consonants D, G, K, S, B, T, P, H, L and R, on the type section 26 normally lie at the printing line, so that, these initial consonants may be normally printed by actuating the primary initial consonant 35 keys. For a similar reason, the primary final consonants L, R, N, M, B, T, G, L, Y and S, on the shiftable type section 27 are normally located at the printing line. The vowel type characters on the stationary, or 40 non-shiftable, type section 24 are always located at the printing line, and they may be printed at any time by actuating the vowel keys. The type sections 26 and 27 may be shifted independently of each other so that 45 the secondary characters on either of said sections may be combined with the primary characters on the other section.

The primary type characters normally lie directly above a row of printing hammers 50 28 (Figs. III, IV and VI) which extend from the rear ends of key levers 29. Each of these key levers forms part of a primary key, and it is pivotally supported by a pivot rod 30. Springs 31 (Fig. III) fitted to the 55 key levers, yieldingly hold said levers in their non-printing positions. When one of the primary keys is actuated one of the printing hammers moves upwardly, thereby forcing the paper 14 onto the inking ribbon 60 20 (Fig. III), at the same time forcing said ribbon onto a type character.

The means for shifting the independent type sections 26 and 27, to locate the secondary type at the printing line, comprises 65 a lever 32 rigidly secured to the shift bars

10 and 12, and a similar lever 32' rigidly secured to the shift bars 11 and 13. The lever 32 is pivotally supported at 33 (Figs. III and IV). A pin 34, projecting from the type section 26, lies in an irregular cam slot 70 35 at the rear end of lever 32. The lever 32' is provided with a similar cam 35' (Fig. VI) for the reception of a pin 34' which extends from the type section 27.

When the shift bars 10 and 12 are depressed, the cam faces of the slot 35 move upwardly, thereby shifting the type section 26 rearwardly to locate its secondary type at the printing line. When the shift bars are released, the lever 32 and the type section 80 are restored by a spring 36 (Fig. IV). It will also be understood that the shift bars 11 and 13 and the cam associated therewith can be actuated to shift the type section 27.

The cams for shifting the type are 85 claimed in an application for patent on improvements in shorthand machines, filed by me Feb. 21, 1917, Serial Number 150,053.

Each individual secondary key, or shift key, is pivoted to one of the shift bars and 90 provided with a finger 40 (Figs. III and IV) which extends over a pin 41 on its companion primary key. The fingers 40 normally rest upon pads 42 carried by the respective shift bars. When one of the secondary keys is depressed, movement is transmitted from its finger 40 to the companion primary key. The secondary key also actuates the shifter to which it is connected so as to shift the type before the primary key 100 reaches its printing position. The pins 41 on the primary keys (Figs. III and IV) are located below the fingers 40 on the secondary keys, so that the primary keys may be depressed without transmitting movement 105 to the secondary keys.

The secondary keys 1, 2, 3, 4 and 5 (Figs. I and II) at the rear of the primary initial consonant keys are all secured to the shift bar 12, the secondary keys J, V, Y, M and N 110 being secured to the shift bar 10, and as a consequence both of said shift bars will move downwardly when any one of these keys is depressed. However, owing to the manner in which the secondary keys are 115 loosely connected to the shift bars, only one of the primary keys will move with the selected secondary key (shift key).

43 designates a universal bar (Fig. III) extending over the key levers 29 and secured 120 to an arm 44, said arm being pivotally supported by the rod 30. I do not deem it necessary to show the various devices which are actuated through the medium of the universal bar.

Fig. VII illustrates a modification in which the secondary keys S are pivoted at 45 to the primary keys P. Each primary key P is provided with a stop pin 46 which normally engages the adjacent secondary 130

key. The secondary keys normally rest upon shift bars 10^a and 12^a respectively, but they are not attached to said shift bars. The primary keys P may be actuated independently of the shift bars. When a secondary key S is depressed it forces one of the secondary keys downwardly, at the same time actuating the shift bars to shift the type as previously described.

10 The modification shown in Fig. VIII comprises secondary keys S' pivotally supported by stationary rods 47 and extending over the shift bars 10^b and 12^b, the free ends of the pivoted keys S' being arranged directly 15 above pins 41' on the primary keys P'.

I claim:

1. A shorthand machine having a key-board including a series of individual shift keys, a series of individual printing keys, 20 each of which is operable by one of said shift keys, a series of type characters each of which is associated with and printed by only one of said printing keys, and a second series of type characters, each of which is 25 printed by the joint operation of a shift key and its companion printing key, the printing keys being operable simultaneously to print selected characters of the first mentioned series, and the individual shift keys 30 being movable simultaneously so as to actuate the series of printing keys, thereby printing all of the characters of the second series.

2. A shorthand machine having a key-board comprising groups of individual consonant keys movable simultaneously to print selected consonants, and a group of individual shift keys actuating a series of said consonant keys to print secondary characters, said individual shift keys being movable simultaneously so as to actuate said series of consonant keys, all at the same time, thereby printing a series of secondary characters.

3. A shorthand machine having a key-board comprising a group of individual initial consonant keys, a group of individual final consonant keys, all of said keys being movable simultaneously to print the initial 50 and final consonants, and said keys being movable independently of each other to print selected consonants, and a group of individual shift keys actuating a series of said consonant keys to print secondary characters, 55 said group of individual shift keys and the series of consonant keys actuated thereby being movable with other consonant keys, so as to simultaneously print a selected combination of consonants and a selected combination of secondary characters.

4. A shorthand machine having a key-board comprising a group of individual initial consonant keys, a group of individual final consonant keys, all of said keys 65 being movable simultaneously to print the

initial and final consonants, and said keys being movable independently of each other to print selected consonants, a group of individual shift keys actuating a series of the initial consonant keys to print secondary 70 characters, and a group of individual shift keys actuating a series of the final consonant keys to print secondary characters, said individual shift keys and the individual consonant keys actuated thereby being movable simultaneously to print a selected combination of secondary characters at the same time. 75

5. A shorthand machine having a key-board comprising a group of individual initial consonant keys, a group of individual final consonant keys, all of said keys being movable simultaneously to print the initial and final consonants, and said keys being movable independently of each other to 80 print selected consonants, a group of individual shift keys actuating a series of the initial consonant keys to print secondary characters, and a group of individual shift keys actuating a series of the final consonant 85 keys to print secondary characters, the individual shift keys and the consonant keys actuated thereby being movable simultaneously to print all of said secondary characters at the same time, and the first mentioned group of individual shift keys being movable with selected keys of the final consonant group to simultaneously print a selected combination of secondary characters 90

95

6. A shorthand machine having a key-board including a series of type shifting keys, and a series of printing keys operable by said type shifting keys, the printing keys being movable independently of each other 100 to print selected primary characters, each type shifting key being operable with a printing key by a single finger to print a selected secondary character, and said type shifting keys being movable simultaneously so as to transmit movement to several printing keys at the same time, thereby simultaneously printing a selected combination of secondary characters. 105

7. A shorthand machine having a key-board including individual primary keys, individual secondary keys each of which is adapted to actuate one of said primary keys, said primary keys being movable independently of each other to print selected primary 110 characters, and secondary type characters each of which is printed by the joint operation of a secondary key and its companion primary key, said individual secondary keys being movable simultaneously by different fingers, so as to print a selected combination of secondary characters in one stroke. 115

8. A shorthand machine having a key-board including alphabetical keys, and a row of numeral keys associated with said 120 125

alphabetical keys, said alphabetical keys being arranged in front of said row of numeral keys, the alphabetical keys being operable by the numeral keys and said alphabetical keys being movable independently of said numeral keys.

9. A shorthand machine having a keyboard including a shifter provided with a series of individual shift keys; and a series of 10 individual printing keys, each of which is operable by one of said individual shift keys.

10. A shorthand machine having a keyboard including a shifter, a series of relatively short individual shift keys each of which is pivoted to said shifter, and a series of printing keys each of which is operable by one of said shift keys.

11. A shorthand machine having a keyboard including a shifter, a series of relatively short individual shift keys each of which is pivoted to said shifter, and a series of printing keys each of which is operable by one of said shift keys, each printing key being movable independently of its companion shift key, and each shift key being provided with an extension adapted to engage its companion printing key.

12. A shorthand machine having a series of printing keys, a shifter common to all of said keys, and a series of individual shift keys for actuating said shifter, each of said printing keys being operable by one of said shift keys, and said individual shift keys being movable simultaneously so as to actuate a number of printing keys at the same time.

13. A shorthand machine having a keyboard including a series of printing keys,

a shift bar, individual shift keys each of which is provided with means for transmitting movement to an individual printing key and also to said shift bar, said printing keys being free to move independently of said shift bars and shift keys, and a series 45 of the individual shift keys being movable simultaneously so as to actuate the shift bar and a series of printing keys at the same time.

14. A shorthand machine having a keyboard 50 including a series of individual shift keys, a shifter common to all of said keys, and a series of individual printing keys movable independently of each other and independently of said shifter to print selected characters, said shifter and the series of printing keys being movable simultaneously to print other selected characters, and each individual shift key being combined with a printing key to provide for the transmission 60 of movement from any selected shift key to a printing key.

15. A shorthand machine having a keyboard including printing keys, individual shift keys at the front of said printing keys 65 and individual shift keys at the rear of said printing keys, each of said printing keys being operable by one of said shift keys.

16. A shorthand machine having a keyboard including two series of shift keys, two 70 series of printing keys, the printing keys being movable independently of the shift keys, and each printing key being operable by one of the shift keys.

In testimony that I claim the foregoing I 75 hereunto affix my signature.

W. S. IRELAND.
